JOSEPH LOUIS KIEFFER, OF MONTREAL, CANADA.

STITCH-FORMING MECHANISM FOR SHOE-SEWING MACHINES.

SPECIFICATION forming part of Letters Patent No. 752,398, dated February 16, 1904.

Application filed July 14, 1902. Serial No. 115,589. (No model.)

To all whom it may concern:

Be it known that I, JOSEPH LOUIS KIEFFER, a subject of the King of Great Britain, residing in the city and district of Montreal, Province of Quebec, Canada, have invented certain new and useful Improvements in Stitch-Forming Mechanism for Shoe-Sewing Machines; and I do hereby declare that the following is a full, clear, and exact description of the invention, such as will enable others skilled in the art to which it appertains to make and use the same.

My invention relates to improved stitch-forming mechanism adapted for shoe and leather sewing machinery of that class known as the "outsole-stitcher," and especially that type forming the stitch known as a "lock-stitch," wherein an upper or bobbin thread and a lower or machine thread are employed and interlocked one with the other.

The object of my present invention is to produce an improved stitch-forming mechanism of the revolving-hook class which shall embody all the advantages of the oscillating hook described in my Patent No. 719,980, dated February 3, 1903, while at the same time embodying the additional advantages which are inherent in the revolving-hook over the oscillating-hook type of apparatus.

The particular object had in view in the invention herein described is to greatly increase the capacity of the machine by doubling or tripling the number of stitches which may be formed in a given space of time. A comparatively slow speed is necessarily inherent in shoe and leather machinery, because of the weight and momentum of the moving parts, which necessitate such slow speed on account of danger of breakage. Now a revolving hook can, other things being equal, be operated at a much greater rate of speed than an oscillating hook, because the motion is, comparatively speaking, continuous, whereas that of the oscillating hook requires to be reversed twice during the formation of each stitch. The inertia of the hook puts a limit, depending on the strength and resistance of the materials, upon the rate of speed at which the hook travels, and hence the revolving hook can be run

at a much greater speed than the oscillating hook.

A further object of this invention is to improve the motion of the parts in carrying the thread over the bobbin, by which friction between the bobbin-case and the box in which it lies is, as far as possible, eliminated. That this is a very important feature of shoe-sewing machines is a matter of experience with all those who have had occasion to test them, because the number of times which the same fibers of thread have to undergo a rubbing action in being drawn over the bobbin is great in proportion to the amount of thread necessary in order to form the drawn-out thread-loop as compared with the finished stitch, and this makes the question of friction by abrasion of the thread during the formation of the stitch an extremely important one. The difference is seen to a marked degree in comparing several of the different machines now on the market, because in some there is so great an abrasion of the thread (although this is not noticeable to the eye or to ordinary inspection) that the stitch cannot be drawn up tight without breaking the thread, and therefore a loose and inferior quality of work is the necessary result.

In my present invention I have so arranged the parts as to practically eliminate altogether the rubbing or bruising of the thread between the bobbin-case and the bracket which supports the same, except at a single point during the formation of a stitch.

It is a further object of my present invention to eliminate altogether a very important but hitherto apparently unnoticed source of abrasion of the thread, which lies in the manner in which the thread is removed from the barbed needle, which brings up the thread-loop through the work. The inventions heretofore produced for delivering the thread from the needle and carrying it around the bobbin have not had sufficient regard for the sharp edge of the barb of the needle whereby every time the thread was removed it was caused to rub or scrape over said barbed edge, and thereby become abraded, and inasmuch as the same fibers were thus cut and abraded over

and over again during the progress of the work it naturally caused a raveling or fraying and considerable weakness of the thread, which had the same result as the fault previously alluded to, that of practically weakening the thread, so that the stitch cannot be pulled up tight.

With these objects and purposes in view my invention consists, substantially, in a hook having a double or forked forwardly-directed nose, one limb of which is adapted to receive the thread, while the other—that is to say, the outer limb—is simply a guide to direct one lap of the thread-loop over the bobbin. These two limbs of the hook take the place, respectively, of the recurved nose and of the body of the oscillating hook described in my former applications. The hook thus formed is attached to a rotating disk at the rear of the bobbin-case and in the center thereof, and on the edge of this disk, at a point just in advance of the nose of the hook, is formed a forwardly-projecting rim or flange which is adapted to serve partly as a shield to cover the point of the needle during the drawing up of the thread-loop by the take-up mechanism and partly to operate the bobbin-case to throw it from one side to the other in connection with the means for preventing the friction of the thread between the bobbin-case and bobbin-bracket, as will be presently referred to.

My invention also comprises a longitudinal or arcuate groove formed in the rear side of the hook, into which the needle is adapted to pass during the delivering of the thread-loop therefrom, combined with a certain cam movement whereby the hook is brought to a stop while the needle is passing into said groove and caused to start again only after the barb of the needle has completely entered the groove and the thread has been completely delivered therefrom.

My invention further consists in the particular form of the inside surface of the bobbin-bracket, which is not, as heretofore was the case, a perfect surface of revolution fitting the bobbin-case all round, but is cut away all around except at three points equally or otherwise spaced around the inner periphery of the bracket, so as to support the bobbin-case from these three points only, but rather from two of these points only, the bobbin being arranged to rest on the bottom or lower of the three bosses or knobs thus formed and slightly also against one of the others, whereby the thread in passing over the bobbin cannot rub between the two surfaces at any more than two points from beginning to end. With this conformation, moreover, is conjoined a finger or trip extending inwardly from the thread-hook or the disk by which it is carried, so as to strike against the bobbin and push it over

from one side to the other in advance of the thread, and thereby just before the thread passes between the bobbin case and bracket at a point of contact of the two they are caused to be separated, so that the thread passes through without friction, and the same operation is performed at the other side of the center. This operation will be understood more clearly from the accompanying drawings and description.

My invention further consists in the peculiar construction and combination of parts, which will be hereinafter described, and more particularly pointed out in the claims.

As many of the features of my present invention can be equally well applied to the oscillating thread-hook formerly invented by me, I have illustrated the oscillating thread-hook in conjunction with the rotating hook to show the application of these features.

The elements and construction of my invention in its most improved form and modifications are shown in the accompanying drawings, in which—

Figure 1 is a side elevation of the new form of revolving thread-hook in the act of forming a stitch, the first stage of the process being shown, in which the hook is entering the thread-loop carried by the needle. Fig. 2 is a similar view, but showing the second step in the formation of the stitch, in which the thread-loop is being delivered from the needle. Fig. 3 shows the third step in the formation of the stitch, in which the thread-loop is being carried over the bobbin. Fig. 4 is a similar view to Figs. 1, 2, and 3, but showing the fourth step in the formation of a stitch, in which the thread is being cast off and the stitch drawn up by the take-up mechanism. Fig. 5 is a similar view showing the last step in the formation of the stitch. Fig. 6 is a central vertical transverse section through the stitch-forming mechanism, the parts being in the position shown in Fig. 1. Fig. 7 is a similar view to Fig. 6, the parts being in the position shown in Fig. 2. Fig. 8 is a similar view showing the parts in the same position as in Fig. 4. Fig. 9 is a perspective view of the thread-hook from the front side. Fig. 10 is a similar view of the hook from the rear side. Fig. 11 is a perspective view of an oscillating thread-hook having my invention applied thereto. Fig. 12 is a front elevation, on an enlarged scale, of a modified form of stitch mechanism, showing more distinctly the method of operating the bobbin-case. Fig. 13 is a similar view of the same device as in Fig. 11, illustrating a subsequent step in the formation of a stitch. Fig. 14 is a perspective view of the bobbin-bracket from the rear side. Fig. 15 is a side elevation of parts of a machine embodying my improvements *in situ*, the rotating hook being shown in central section to illustrate the

timing of the relative movements of the thread-hook and needle; and Fig. 16 is a velocity-diagram of the movements of the hook.

The same numerals of reference denote like parts in all the figures of the drawings.

In the drawings, 15 designates a block, as of metal, which is herein called the "thread-hook block," because it serves to support the thread-hook and the other operative parts of the stitch-forming mechanism. This block is supposed to be secured on the work-head of the machine and is not fully shown herein, because its form is a matter of indifference to the present invention, although that shown in my previous application, Serial No. 105,493, filed May 1, 1902, is an appropriate form. This block 15 is formed with a shallow cylindrical recess 16 in its front face, in which operates the revolving hook 17, which is formed as an arcuate extension of the thread-hook disk 18, mounted to rotate upon a spindle 19, which passes through the rear side of the block 15. The thread-hook disk 18 forms the rear of the bobbin-box, which is closed at the front side by a suitable bobbin-bracket 20, secured by bolts 21 to the block 15, and having a depending annular portion 22, which serves to loosely confine the bobbin-case 23, this case being, as shown in Figs. 6, 7, and 8, of a double-conical form having a surface of revolution with a sharp elbow 24, which is adapted to divide the thread-loop. The front face of the bobbin-case 23 is left open by means of the central aperture 25, formed in the bobbin-bracket. The inner side 26 of this bobbin-bracket is of roughly-conical form, corresponding to the exterior surface of the bobbin-case; but it has not a surface of revolution, because, as shown, it has three irregularly-spaced bosses thereon, (designated, respectively, 27, 28, and 29.) It is on these three bosses that the bobbin-case 23 rests; but it does not rest on all three at once, because it is loose within the box and has a considerable amount of play and is caused to be thrown from side to side by the motion of the thread-hook in a manner which will be described. The lowermost boss 27 forms a constant resting-point for the bobbin-case; but the other two bosses 28 and 29 are merely buffers which alternately check its motion at the side, so that the bobbin-case rests first against one and then against the other. The bosses 28 and 29 are not at equal distances from the bottom boss 27; but, as shown, the boss 28 on the right or rising side of the thread-hook is about ninety degrees from the boss 27, whereas the other boss, 29, on the left or descending side of the thread-hook is about one hundred and sixty degrees from the boss 27. The ring 22 of the bobbin-bracket has also a notch 30 in the center of the boss 27, which coacts with a depending lip 31, formed on the bobbin-case, to prevent the same from rotating

during the operation of the machine, while at 65 the same time enabling the thread to be slipped easily thereover and to pass out from between the bobbin case and bracket.

Before describing further the mode of operation of the thread-hook in connection with the bosses 27, 28, and 29 and the bobbin-case I will describe the general form and mode of operation of my improved revolving thread-hook, which is shown in Figs. 1 to 8, inclusive, and in enlarged perspective view 75 in Figs. 9 and 10. The disk 18 has at the center thereof a bored hub 32, through which passes the shaft 19, which projects at the rear of the block 15, and has also mounted thereon back of the hub 32 a screw-gear pinion 33, 80 having a long bearing-sleeve 34 projecting into the bearing-block 35, secured on the work-head of the machine, and the several parts are clamped up together on the shaft 19 by means of lock-nuts 36 passing over the 85 screw-threaded end 37 of the shaft. In order to tighten the lock-nuts 36 in place, I preferably recess the end of the shaft 19 and split the same laterally, as by cuts 37^a, and insert in the recessed end a wedge-screw 37^b. The 90 screw-gear and thread-hook disk are also preferably-keyed together in proper relative position by any suitable means, such as interlocking lugs 38.

With the screw-gear pinion 33 coacts a similarly-formed pinion 39, whose shaft 40 is at right angles to the shaft 19, but does not intersect the same, and the shaft 40 is kept in continuous but irregular rotation by means of suitable cam mechanism, so as to give the 95 proper motions, which will be hereinafter described, to the thread-hook 17 in its rotation.

The thread-hook 17 is formed, as shown, with a double forwardly-directed nose having two limbs, (designated, respectively, 41 and 42,) 105 the upper of which, 41, is the effective or operative limb, which serves to remove the thread-loop from the needle and carry it around the bobbin, while the lower limb, 42, of the nose is somewhat shorter than the limb 110 41 and has its forward end directed somewhat backwardly, so that it is inserted behind the rear lap of the thread-loop and serves to push it out and cause it pass through the bight or slot 43 between the two limbs of the hook. 115 The hook 17, behind the junction of the two limbs 41 and 42, has a reduced neck 44, which serves to permit the easy passage of the thread over the bobbin in a manner which will be seen from the subsequent description. Moreover, what is a special feature of this invention, the upper limb 41 of the hook has in its rear surface a longitudinal or arcuate groove 45, which is tapered from no depth at its forward end 46 to a sufficient depth to completely 120 inclose the barbed end of the needle 59 to a point a considerable distance back of the barb. This groove coacts with the needle by means

of the cam motions given to the hook and needle, respectively, in such a manner as to leave the thread-loop clear of the barb of the needle without causing abrasion on the sharp edge 5 of the barb, and the particular motions by which this result is produced will be described later.

The front side of the thread-hook disk 18 is dished out to form a shallow recess 47, having 10 conical sides and corresponding to the shape of the bobbin-case, so as to allow the same to sit loose therein; but it only touches the bobbin-case normally at one point—that is to say, the point designated herein, 48—which is in 15 the shape of a slightly eccentric heel formed just in advance of the point of the upper limb 41 of the hook. The object of this is to push the bobbin-case at all times into a position farthest from the point of the hook, and with 20 it coact the three bosses 27, 28, and 29, so as to push the bobbin-case over first to the left and then to the right as the hook revolves. In advance of the heel 48 is formed an outwardly-projecting rim 49, which forms a shield or 25 guard for the barb of the needle during the drawing up of the thread-loop after its passage around the bobbin and to prevent the loop from becoming entangled with the needle.

In Fig. 15 I have shown in side elevation 30 and partly in section the hook and needle, together with their cams and cam-levers, in order to illustrate the interaction of the parts which form a part of my invention. At 61 is shown the main shaft of a shoe-sewing machine of any suitable type, on which shaft is keyed a cam-block 62 by means of the key 63. This cam-block has a cam-groove on each side, (designated 64 65,) in which work the rollers 66 67 of a pair of interacting cam-levers 68 69, which are pivoted on pins 70 71, the former of these levers being arranged to occupy a generally vertical position and the latter a horizontal. On the end of the shaft 40 is formed a crank 72, having a pin 73, on 45 which is pivoted the end of a link 74, which is joined by a pivot-pin 75 at an intermediate point thereof to the end of the lever 69, while its upper end is connected by a link 76, pivoted at 77 to the upper end of the lever 68. 50 The formation of the cam-grooves 64 65 is such as to cause the crank 72 to rotate continuously in one direction, being counter-clockwise, as shown by the arrow in Fig. 15, the shaft 61 also rotating in a counter-clockwise direction, and not only this, but the formation of the cam-grooves 64 65 is such as to 55 impart a variable rotative speed to the crank 72, and hence to the thread-hook, the variations being such as will be explained herein-after. The needle (designated 59) is carried by the needle-block 78, which rotates about its axis 79 and has formed thereon a gear-segment 80, which cooperates with the teeth 81 of a gear-segment formed on the end of 60 the needle-lever 82, which is pivoted on a pin

at the back of the machine (herein shown as coaxial with the pin 71) and is operated by a roller 83, mounted on it at an intermediate point and running in a cam-groove 84 in the side of another cam-block behind the cam-block 62, as is usual in such machines. At 70 85 is shown a needle-guide which embraces the stem of the needle and at 86 the table on which the work rests, these being customary parts of the mechanism and forming no part 75 of the present invention.

The mode of operation of my improved rotating hook may be described as follows: The bobbin-case, mounted in its box, rests loosely against the lower boss 27 of the bracket, in 80 which position it is slightly below the axis of the revolving hook. Supposing now the thread-hook (which in the present drawings rotates in a counter-clockwise direction, as shown by the arrows) to be in the position 85 shown in Fig. 1, in which the needle has reached the top of its stroke, carrying a thread-loop 50 through the work 51. The point 41 of the hook is so positioned as to enter between the two laps of this loop in the manner shown 90 in Fig. 1, and as the motion of the hook proceeds the lower limb 42 of the hook passes beneath and behind both laps and causes the rear lap to be inserted into the bight 43. When the hook has reached the position shown in 95 Fig. 2, its motion ceases for an instant, and during this period of rest the needle moves forwardly and enters the groove 45, having previous to that time remained outside this groove. The advance of the needle is sufficient to entirely deliver the thread-loop therefrom, leaving it cast off the barb of the needle onto the limb 41 of the hook, (see Figs. 7 and 15,) and after this cast-off movement has 100 been accomplished, which occupies but an instant, the hook moves forward again and carries the loop around the bobbin in the manner indicated in Fig. 3, the two laps of the loop passing, respectively, on opposite sides of the bobbin, which is enabled to take place 105 by means of the reduced neck 44. It will be observed, further, that the ring 26 of the bobbin-bracket has on its inner right side adjacent to the boss 27 a slight nick or recess 51^a, which further enables one lap of the thread-loop to pass around the bobbin without excessive friction. Further, it will be noticed that when the thread-hook reaches the position shown in Fig. 2 and after that the heel 48 thereof will strike against the bobbin-case 110 and throw it over, so as to cause it to rest against the boss 29, as indicated, and in this case the thread can pass between the boss 28 and the bobbin-case without touching the former. When, however, the hook reaches the 115 position shown in Fig. 3, the heel 48 now strikes the bobbin-case from the other side and throws it back so as to rest against the boss 28, and the boss 28 having been now 120 passed the thread can likewise pass the boss 125 130

29 without friction thereon. By further revolution of the thread-hook the loop is cast off, as shown in Fig. 4, and is instantly drawn up by the take-up mechanism, during which operation the shield-plate 49 covers the point of the needle in the manner above stated. The thread therefore is carried completely around the bobbin without being subjected to friction between the latter and its supporting parts, except at a single point—that is to say, at the lower boss 27, on which the bobbin-case is supported.

In Fig. 16 is given a velocity diagram to illustrate the velocity of the thread-hook at each point of its revolution. The thread-hook is shown at the center of the diagram in its zero position, the zero-point being taken on a line 87, extending vertically downward from the central point O. The velocity of the thread-hook at any point of its revolution is indicated by that portion of a radius-vector included between the circle 88 and the curve 89. The numerals, ranging from 1 to 20 on the outside of the circle 88, represent equal angles passed through by the thread-hook, the corresponding abscissas representing velocity being drawn in each case. On the inside of the circle is a second series of numerals 1 to 20, which represent the positions of the hook at equal intervals of time. The positions of these angles are taken for a point on the hook lying in the line 87 in the zero position.

It will be seen from the diagram that the motion of the hook starting from the zero position increases uniformly up to the position 7, and from there decreases again to the position 14, this being during the operation of carrying the thread over the bobbin after the same has been released from the needle, and which therefore occupies but about four-twentieths of the time of a complete cycle. At the position 14 the hook becomes nearly or quite stationary, giving time for the successive operation of the take-up, the feed mechanism, the needle, and the looper, this occupying about twelve-twentieths of the time of a complete cycle, and at the end of this time the thread-hook again advances as rapidly as possible to its zero position, where it comes to a stop long enough to allow the needle 59 to move forward into the groove 45, as already explained, and cast off the thread-loop drawn up by it during the time interval 4 to 16, whereupon another cycle is commenced. It will be seen that at the zero-point a small loop is formed in the curve 89 within the circle 88, indicating that a small backward motion may be given to the hook, if found desirable, during the period 18 to 20, which will absolutely secure that the thread-loop is pressed against the stem of the needle during the time that the latter is entering the groove 45, or to counteract the tendency of the thread-hook to a slight torsional bending due to the sudden checking of its forward momentum. By

following out the cam-grooves 64, 65, and 84 it will be seen that they are so arranged as to give the thread-hook the motion illustrated in Fig. 16, and also during the interval 4 to 16 to advance the needle and again retract it 70 to its highest position, and then to slightly again advance it in the interval 18 to 20. The thread-hook is shown as having a very slow advance movement during the period 14 to 17, it being limited in its advance to the position 75 17 up to the end of the time interval 16 in order to give time for the needle to return to its original position, carrying the thread-loop before the point of the thread-hook crosses the needle. 80

It will be understood that the motion of the thread-hook thus described is practically continuous and nearly uniform, except at two points—that is to say, in the position shown in Figs. 4 and 5 and in that shown in Fig. 2. 85 In the former of these it stops or is retarded during a short interval to give time for the thread to be taken up and also for the advance of the needle through the work to form an additional thread-loop. In the second position it stops to enable the loop carried by the needle to be cast off without any abrasion of the thread against the barb. The latter is an important feature of this invention inasmuch as all previous devices for delivering 90 the thread-loop from the needle have entirely overlooked this point or have failed to solve it satisfactorily, so that the thread was carried off the barb of the needle so as to scrape or rub thereon, and thereby cause the fibers 100 of the thread to become broken. The instantaneous stoppages of the thread-hook, however, are comparatively unimportant when considered in connection with the oscillating hook, because the latter had not only to be 105 stopped at a certain point in its motion, but it had additionally to have its motion reversed twice in a single cycle, and the reversal of so heavy a part necessarily requires time. In consequence I find that I can operate my present revolving hook at a much greater speed than the oscillating hook, so as to form from 110 six to eight hundred stitches per minute. As, however, some of the important features of this hook may be advantageously applied to 115 the oscillating hook, I have also herein illustrated the latter (see Fig. 11) as provided with operating mechanism in connection with the peculiarly-formed bobbin-bracket shown in Fig. 14, and the mode of operation has been 120 illustrated on an enlarged scale in Figs. 12 and 13. This thread-hook, (designated 52,) as described in my former application, consists of a forwardly-directed point 53, a recurved nose 54 behind the point, and a grooved 125 tail-shield 55. A groove 56 is also formed in the rear face of the hook, into which a needle passes in the operation of delivering the thread from the needle. In this case just behind the nose 54 is provided a triangular hump 57, 130

which projects beyond the nose 54, as shown in Figs. 12 and 13, a sufficient distance to strike against the bobbin at the side and to throw it to one side or the other, so as to rest 5 first against the boss 29 and subsequently against the boss 28 in advance of the passage of the thread between these bosses and the bobbin-case. The proper eccentric positions occupied by the bobbin-case are shown in 10 each of these figures. The center of the bobbin-case must of course be normally a sufficient distance below the axis of the thread-hook to enable the hump 57 to pass over the top thereof. The operation of this form of 15 the device is precisely similar to that first described, because the hump 57 takes the place of the heel 48 and serves the same function of tipping over the bobbins lightly in advance of the hook.

20 While I have shown in the accompanying drawings the preferred form of my invention, it will be understood that I do not limit myself to the precise form shown, for many of the details may be changed in form or position without affecting the operativeness or utility of my invention, and I therefore reserve the right to make all such modifications as are included within the scope of the following claims or of mechanical equivalents 25 to the structures set forth.

Having thus described my invention, what I claim as new, and desire to secure by Letters Patent, is—

1. In a stitch-forming mechanism for shoe-sewing machines, a thread-hook comprising a forked nose, one limb of which is adapted to enter and deliver the thread-loop from the needle, and the other to guide the rear lap of the loop into the bight of the hook.

40 2. A stitch-forming mechanism for shoe-sewing machines comprising a barbed needle adapted to enter the work and bring up a thread-loop therethrough, and a continuously-rotating thread-hook having a forwardly-directed forked nose, the inner limb of which is longer than the outer and is adapted to enter the thread-loop and deliver it from the needle, and the outer limb of which is adapted to push forward both laps of the thread-loop 45 and cause the rear lap to fall into the bight of the hook.

3. A stitch-forming mechanism for shoe-sewing machines comprising a barbed needle adapted to enter the work and bring up a 55 thread-loop therethrough, and a continuously-rotating thread-hook having a forwardly-directed forked nose, the inner limb of which is longer than the outer and is adapted to enter the thread-loop and deliver it from the needle, and the outer limb of which is adapted to push forward both laps of the thread-loop 60 and cause the rear lap to fall into the bight of the hook, said upper limb of the hook having a groove in its inner face into which the needle is adapted to pass.

4. A stitch-forming mechanism for shoe-sewing machines comprising a barbed needle adapted to enter the work and bring up a thread-loop therethrough, a continuously-rotating thread-hook having a forwardly-directed forked nose, the inner limb of which is longer than the outer and is adapted to enter the thread-loop and deliver it from the needle, and the outer limb of which is adapted to push forward both laps of the thread-loop and cause 70 the rear lap to fall into the bight of the hook, said inner limb of the hook having a groove in its rear face into which the needle is adapted to pass, means for rotating the hook and stopping the same at a point where the groove 75 is opposite the needle, means for thereafter causing the needle to enter the groove while the hook is stationary and leave the thread on the hook, and means for thereafter continuing the rotation of the hook, substantially as 80 described.

5. A stitch-forming mechanism for shoe-sewing machines comprising a barbed needle adapted to enter the work and bring a thread-loop therethrough, a rotating disk forming 90 the rear of a bobbin-box, a bobbin-bracket closing the front of said box, a bobbin loosely mounted in said box, a thread-hook having a forwardly-directed forked nose extending from the periphery of said disk, the upper limb of said nose being adapted to enter the thread-loop and deliver it from the needle, and the lower limb being adapted to push back 95 the rear lap of the loop, and a shield adapted to cover the point of the needle subsequent to the casting off of the thread-loop and during its drawing up by the take-up motion.

6. A stitch-forming mechanism for shoe-sewing machines comprising a barbed needle adapted to enter the work and bring a thread-loop therethrough, a rotating disk forming the rear of a bobbin-box, a bobbin-bracket closing the front of said box, a bobbin loosely mounted in said box, a thread-hook having a forwardly-directed forked nose extending from the periphery of said disk, the upper limb of said nose being adapted to enter the thread-loop and deliver it from the needle, and the lower limb being adapted to push back the rear lap of the loop, and a shield adapted to cover the point of the needle subsequent to the casting off of the thread-loop and during its drawing up by the take-up motion, the upper limb of 100 said thread-hook having a groove in its rear face into which the needle is adapted to enter 105 and to leave the thread-loop on the hook.

7. A stitch-forming mechanism for shoe-sewing machines comprising a barbed needle adapted to enter the work and bring up a thread-loop therethrough, a rotating disk forming the rear of a bobbin-box, a bobbin-bracket closing the front of said box, a bobbin loosely mounted in said box, a thread-hook having a forwardly-directed forked nose 110 extending from the periphery of said disk, 115

the upper limb of said nose being adapted to enter the thread-loop and deliver it from the needle, and the lower limb being adapted to push back the rear lap of the loop, a shield 5 adapted to cover the point of the needle subsequent to the casting off of the thread-loop and during its drawing up by the take-up motion, the upper limb of said thread-hook having a groove in its rear face into which the 10 needle is adapted to enter and to leave the thread-loop on the hook, means for rotating the hook continuously in one direction, means for instantaneously stopping the hook at a point where the groove is opposite the point 15 of the needle, means for advancing the needle into the groove during the rest period of the hook so as to leave the thread-loop upon the hook, means for subsequently advancing the hook to carry the loop over the bobbin, and 20 means for temporarily stopping or retarding the motion of the hook during the casting off of the thread-loop.

8. In a stitch-forming mechanism, in combination, a bobbin-case, a circularly-moving 25 member adapted to carry a thread thereover and a bobbin-bracket supporting the case, the adjacent surfaces of the bobbin case and bracket being so conformed to each other as to touch in only three possible points, so situated with respect to each other that each point 30 lies on the opposite side of a diameter from the other two.

9. In a stitch-forming mechanism for shoe-sewing machines, in combination with a bobbin-case, a bobbin-box, and the hook, of a bobbin-bracket having a ring forming the cover 35 of the bobbin-box, said ring being cut away on its inner surface to form three bosses on the lower one of which the bobbin-case is 40 adapted to rest, and against the upper two of which the bobbin-case is adapted to rest alternately.

10. In a stitch-forming mechanism, the combination of a bobbin-box, a bobbin-case loosely 45 mounted therein, the hook and a bobbin-bracket forming the cover of said box and having three raised points around its periphery, upon one of which the bobbin-case is adapted to be supported, and against one of the other 50 two of which the bobbin-case is adapted to alternately rest.

11. In a stitch-forming mechanism, the combination of a bobbin-box, a bobbin-case loosely 55 mounted therein, a bobbin-bracket forming the cover of said box and having three raised points around its periphery, upon one of which the bobbin-case is adapted to be supported, and against one of the other two of which the bobbin-case is adapted to alternately 60 rest, and means for throwing the bobbin-case first to one side and then to the other in advance of the passage of the thread between said raised points and the bobbin-case.

12. A stitch-forming mechanism for shoe-sewing machines comprising a barbed needle 65

adapted to enter the work and bring a thread-loop therethrough, a thread-hook block having a shallow cylindrical groove therein forming the bobbin-box, a thread-hook adapted to move around the periphery of said box, a bracket forming the cover of said box, a circular bobbin-case loosely mounted in said box, a series of raised points around the inner margin of said bracket upon which said bobbin-case rests, and means carried by said thread-hook for throwing the bobbin-case over from one side to the other in advance of the passage of the thread around the same, substantially as described. 75

13. A stitch-forming mechanism for shoe and leather sewing machinery comprising a thread-hook block having a shallow cylindrical recess therein forming a bobbin-box, a spindle passing through the rear of said block in the center of said recess, means for unevenly rotating said spindle, a disk mounted on the forward end of said spindle within said recess and forming the rear face of said bobbin-box, an arcuate thread-hook mounted on said disk and having a forwardly-directed forked nose, 90 the inner limb of said nose being longer than the outer, a bobbin-bracket having a ring closing the front of said bobbin-box, a bobbin-case loosely mounted in said box, means for preventing said bobbin-case from rotation, and 95 a shield adapted to cover the barbed needle during the drawing up of the thread-loop.

14. A stitch-forming mechanism for shoe and leather sewing machinery comprising a thread-hook block having a shallow cylindrical recess therein forming a bobbin-box, a spindle passing through the rear of said block in the center of said recess, means for unevenly rotating said spindle, a disk mounted on the forward end of said spindle within said recess 100 and forming the rear face of said bobbin-box, an arcuate thread-hook mounted on said disk and having a forwardly-directed forked nose, the inner limb of said nose being longer than the outer, a bobbin-bracket having a ring closing the front of said bobbin-box, a bobbin-case loosely mounted in said box, means for preventing said bobbin-case from rotation, 105 said bobbin-bracket having a series of three raised points or bosses on its inner periphery, 110 which serve as supports and stops for said bobbin-case, and means carried by said thread-hook in advance of the nose thereof for throwing the bobbin-case over to the side farthest from the nose, whereby the thread is permitted 115 to pass over the bobbin-case without friction between it and its supports, substantially as described.

15. A stitch-forming mechanism for shoe and leather sewing machinery comprising a 125 thread-hook block having a shallow cylindrical recess therein forming a bobbin-box, a spindle passing through the rear of said block in the center of said recess, means for unevenly rotating said spindle, a disk mounted on the for- 130

ward end of said spindle within said recess and forming the rear face of said bobbin-box, an arcuate thread-hook mounted on said disk and having a forwardly-directed forked nose, the inner limb of said nose being longer than the outer, a bobbin-bracket having a ring closing the front of said bobbin-box, a bobbin-case loosely mounted in said box, means for preventing said bobbin-case from rotation, 5 said bobbin-bracket having a series of three raised points or bosses on its inner periphery which serve as supports and stops for said bobbin-case, and an eccentric heel or hump carried by said thread-hook and adapted to 10 strike against the side of the bobbin-case for throwing the bobbin-case over to the side farthest from the nose, whereby the thread is permitted to pass over the bobbin-case without friction between it and its supports, substantially as described.

16. A stitch-forming mechanism for shoe-sewing machines comprising a thread-hook block having a shallow cylindrical recess therein, a shaft passing through the rear of the 25 block in the center of the recess, means for unevenly rotating said shaft continuously in one direction, a thread-hook disk secured on the forward end of said shaft within said recess and having a dished front face adapted 30 to conform with the shape of the bobbin-case and to form the back of the bobbin-box, a bracket coacting with said disk to form the cover of said bobbin-box and having a ring adapted to surround the bobbin-case, a bobbin-case loosely mounted between said disk 35 and ring, a series of three raised points respectively at the bottom and on opposite sides of the inner periphery of said ring on the first of which the bobbin-case is supported and 40 against one of the other two of which the bobbin-case rests alternately, a thread-hook having a forwardly-directed nose adapted to enter the thread-loop and deliver it from the needle, a barbed needle coacting with said 45 thread-hook, and an eccentric heel or hump in advance of said thread-hook, whereby the bobbin-case is thrown over in advance of the

passage of the thread thereover to cause it to pass between it and its supports frictionlessly.

17. A stitch-forming mechanism for shoe-sewing machines comprising a thread-hook block having a shallow cylindrical recess therein, a shaft passing through the rear of the block in the center of the recess, means for unevenly rotating said shaft continuously in 55 one direction, a thread-hook disk secured on the forward end of said shaft within said recess and having a dished front face adapted to conform with the shape of the bobbin-case and to form the back of the bobbin-box, a 60 bracket coacting with said disk to form the cover of said bobbin-box and having a ring adapted to surround the bobbin-case, a bobbin-case loosely mounted between said disk and ring, a series of three raised points 65 respectively at the bottom and on opposite sides of the inner periphery of said ring on the first of which the bobbin-case is supported and against one of the other two of which the bobbin-case rests alternately, a thread-hook having 70 a forked forwardly-directed nose, the inner limb of which is longer than the upper and provided with a groove in its rear face, a barbed needle adapted to enter the work and bring a thread-loop therethrough and to coact 75 with said hook, means for advancing said hook to a point opposite said needle and then momentarily stopping said hook, means for subsequently advancing the needle into said groove a sufficient distance to clear the loop 80 from the barb thereof and leave it on the hook, means for thereafter advancing the thread-hook and carrying the loop over the bobbin, and an eccentric heel or hump adapted to strike against said bobbin-case slightly in advance of the hook and throw it over so as to 85 permit the thread-loop to pass between the bobbin-case and its supports frictionlessly.

In witness whereof I have hereunto set my hand in the presence of two witnesses.

JOSEPH LOUIS KIEFFER.
